UNITED STATES PATENT OFFICE.

PAUL ELIE JULES CHABBERT, OF CASTRES, FRANCE.

COUCH OR BED PAN.

Application filed January 17, 1923. Serial No. 613,278.

To all whom it may concern:

Be it known that I, PAUL ELIE JULES CHABBERT, citizen of the French Republic, and residing at Castres, Tarn, France, have 5 invented certain new and useful Improvements in Couch or Bed Pans, of which the following is a specification.

The present invention has for object a flexible and removable couch or bed-pan for 10 the purpose of isolating or holding away recumbent infants from their urine or other dejections, and for protecting or preserving their linen or bedding from saturation by these discharges, characterized by the combination of an apertured cover or apron with a flexible pan forming a collector, the apron being held away from the bottom of the pan by a suitable support so as to prevent any liquid from reaching the upper face of the 15 apron. Whilst more particularly intended for children the invention can however be employed for adolescents or adults.

The annexed drawing represents by way of example, one form of constructing the 20 device according to the present invention.

Figure 1 is a plan view.

Figure 2 is a vertical section on line 2—2 of Figure 1.

Figure 3 is a plan view of the pan.

30 Figures 4 and 5 are vertical sections, longitudinally and transverse respectively, on lines 4—4 and 5—5 of Figure 3.

Figure 6 is a part plan view of the cover or apron.

35 Figures 7 and 8 are part vertical sections, longitudinal and transverse respectively, on lines 7—7 and 8—8 of Figure 6.

Figure 9 is a plan view of the support intended to maintain the apron or cover at a 40 certain height from the bottom of the pan in such a way as to insulate the apron from dejections which are retained by the pan.

Figures 10 and 11 are part vertical sections, longitudinal and transverse respectively, on lines 10—10 and 11—11 of Figure 9.

The pan *a* in which are arranged the insulating support or separator *b* and the apertured cover or apron *c*, is made of a 50 single piece and of a waterproof textile or other material. The sides *a'* of the pan are turned up at a right angle and connected at the four corners in such a way as to form a collecting basin of which the dimensions in width and in length are the same as those of the apron *c* and of the insulating support 55

b, and of which the height or depth corresponds with the thickness of these two members *b* *c* when superposed. The sides *a'* are inturned, parallel to the bottom of the pan, 60 so as to form a flange *a*², which, when the insulating support *b* and the table *c* are placed in the pan *a*, acts as a narrow marginal cover (Figures 1 and 2) for the apron in order to hold the three members together. 65

The insulating support or separator *b* is a moulding in rubber of triangular ribs or beadings *b'* which intercross and form a grid or checkerwork of which the longitudinal and transverse beadings have their upper face in the same plane; the four beadings at the periphery project as at *b*² from the lower face of the grid, and bosses *b*³ at each intersection of the beadings form an equal projection, so that when the insulating support *b*⁵ is placed upon a flat surface it bears upon the surface only by the peripheral projection *b*² and the bosses *b*³. 70

The apron *c* is a moulding in rubbr of triangular ribs or beadings of equal height 80 which intercross and form a grid or checkerwork of which the longitudinal and transverse beadings have their upper faces in the same plane; the four beadings at the periphery project as at *c*' from the lower face of the grid, and bosses *c*² situated as hereafter explained, form an equal projection such that when the apron *c* is arranged upon a plane surface it bears upon such surface 85 only by means of its peripheral projection and the bosses *c*².

The insulating support or separator *b* and the apron *c* when superposed coincide at their peripheries; their two grids have their meshes of two very different dimensions, those of the separator being much larger than those of the apron. The bosses *b*³ of the separator are placed at the intersections of the beadings, while those of the apron are arranged in such a way as each to 90 bear upon the ribs of the separator only between two of its adjacent bosses, as shown in Figure 9 by the crosses *x*. 95

In order to put the separator *b* and the apron in place in the pan *a*, or to remove 100 them therefrom, it is sufficient to cause the longitudinal edges *a'* of the pan *a* to assume a shape such as that shown in dotted lines in Figure 3: the return movement of the pan fixes in place the superposed members 110 and locks them together in the working position, shown in Figures 1 and 2.

5 The couch or bed-pan thus constructed is placed in the cradle, the infant being laid upon the apron portion, which will then drain off, when such discharges occur, the liquid dejections which will be retained in the pan.

10 The thickness of the insulating support and the useful capacity of the spaces afforded, will place the recumbent infant out of contact with its dejections; the water tightness of the pan will preserve the bed linen from contact therewith and saturation thereby.

15 The use of this couch or bed-pan is obviously not restricted to infants alone; it can be employed for persons of all ages, and for all those who being incontinent or sick, evacuate in the seated or prone position, dejections or washing liquids.

20 The use of an insulating support and of an apron portion each having bosses of which the quincunx relation when they are superposed, enables the construction of a couch or bed-pan having great flexibility 25 in all directions, by utilizing the elasticity given by the points of support of the apron upon the separator, the apron-bosses bearing out of line upon the beadings of the separator between the bosses.

30 What I claim is:

1. A flexible and removable couch or bed-pan adapted to insulate recumbent persons from their liquid dejections and to protect the bed linen, comprising a pan, of flexible 35 and waterproof material, forming a collector, an apertured cover member, composed of a grid of moulded rubber, with bars intercrossing in the same plane upon

their upper face and projections upon the lower face of said grid-bars, and means for 40 separating the said cover member from the bottom of the pan and for allowing dejections to drain through the apertured cover member into the bottom of the pan.

2. A flexible and removable couch or bed-pan adapted to insulate recumbent persons from their liquid dejections and to protect the bed linen comprising a pan, of flexible and waterproof material, forming a collector, an apertured cover member, and a 50 grid of moulded rubber, with bars intercrossing in the same plane upon their upper face, and projections upon the lower face of said grid bars, said grid being located between the bottom of the pan and the apertured apron member, for the purposes described.

3. A flexible and removable couch or bed-pan adapted to insulate recumbent persons from their liquid dejections and to protect 60 the bed linen, comprising a pan, of flexible and waterproof material, forming a collector, an apertured cover member, composed of a grid of moulded rubber, with bars intercrossing in the same plane upon their upper 65 face and projections upon the lower face of said grid bars, and another grid of moulded rubber, with bars intercrossing in the same plane upon their upper face, and projections upon the lower face of said grid-bars, said grid being located between the bottom of the pan and the apertured apron member, for the purposes described.

In testimony whereof I have signed my name to this specification.

PAUL ELIE JULES CHABBERT.
